UNITED STATES PATENT OFFICE.

LEWIS CALVIN BULLOCK, OF MILESBURG, PENNSYLVANIA.

IRONING-TABLE.

No. 823,580.

Specification of Letters Patent.

Patented June 19, 1906.

Application filed August 9, 1904. Serial No. 220,104.

To all whom it may concern:

Be it known that I, LEWIS CALVIN BULLOCK, a citizen of the United States, residing at Milesburg, in the county of Center and State of Pennsylvania, have invented new and useful Improvements in Ironing-Tables, of which the following is a specification.

The invention relates to an improvement in tables, particularly of that class in which several valuable articles are combined with the table, whereby to materially increase its efficiency and scope of use.

The present invention is directed mainly to combining with a table an ironing-board and bosom-board and to arrange the parts so that these features may be readily moved into position for use when desired without materially interfering with the use of the table as such.

The invention further provides for the convenient adjustment of the height of the table to readily adapt the same for use with the ironing adjuncts.

The invention in its preferred form is illustrated in the accompanying drawings, in which—

Figure 1 is a side elevation of my improved table, showing the ironing-board and bosom-board in position for use, the table-legs being positioned to maintain the table in its highest position. Fig. 2 is a longitudinal central section of the table, the legs being adjusted to support the table in its lowest position. Fig. 3 is an end elevation of the same. Fig. 4 is an enlarged broken sectional view through the table, showing the bosom-board in inoperative or lowered position. Fig. 5 is a bottom plan of the table proper. Fig. 6 is a detail perspective illustrating the attachment of the ironing-board to the table. Fig. 7 is a cross-section on line 7-7 of Fig. 1. Fig. 8 is a sectional view through the outer end of the table proper, the plate 34, and one of the fastening connections between said plate and removable table.

Referring to the drawings, wherein like parts are designated by similar reference-numerals throughout the several views, 1 represents the table proper, which may be of any desired dimension and is provided on its under side with end strips 2 and side strips 3. Each end strip 2 is provided with a longitudinally-extending metallic strip 4, the ends of which are turned down to form ears 5. A table-leg 6 is pivotally secured to each ear 5 by a pivot-pin 7, the legs being preferably arranged on the inner side of the ears. It will

thus be understood that the legs depend in pairs from each strip 4, being pivotally connected thereto and braced against independent movement by brace-strips 8, secured to the legs and crossed, as clearly shown in Fig. 3.

To vertically adjust the height of the table, I provide means for altering the inclination of the legs with relation to the table. The means noted comprise pairs of hanger-bars 9, arranged at the opposite sides of the table and pivotally mounted at their upper ends on the sets of pivot-pins 7 and at their lower ends on a transverse rod 10, which rod is arranged transversely and centrally of the table and below the same. Adjusting-bars 11, similarly arranged in pairs, are pivotally connected at their outer ends to the legs 6, near the lower ends of the latter, and are slotted at their inner ends, as at 12, to embrace the transverse rod 10. By preference the hanger-bars 9 of each pair are spliced on the rod 10 on either side of the coacting pairs of adjusting-bars 11, whereby the ends of said bars 9 act as clamping members to hold the bars 11 in adjusted position. The ends of rod 10 are threaded and are provided with fixed nuts 13, against which the inner hanger-bar 9 of each pair of hanger-bars abuts when the parts are assembled, the threaded ends of the rod being provided with the usual thumb-nuts 14, whereby to clamp the adjusting-bars and hanger-bars in fixed relation against the nuts 13 and to the transverse rod 10.

By the construction described it will be evident that the adjusting-bars 11 may be moved to alter the inclination of the legs 6 with relation to the table, and as the upper ends of said legs are pivotally connected with the table such movement will elevate or depress the table proper, the thumb-nuts 14 securing the parts in adjusted position.

The bosom-board 15 is by preference arranged centrally of the table 1, being adapted when elevated to operative position to project above said table and when lowered into inoperative position to fit within an opening 16 formed in the table, it being understood that the bosom-board is of the usual contour and that the opening 16 is arranged to snugly receive said board, whereby when the board is lowered the surface of the table is unbroken. The bosom-board is supported by the table proper through arms 17, pivotally connected to ears 18, pendent from a strip 19, secured to one of the end bars 2, the opposite ends of arms 17 being pivotally connected to

ears 20, pendent from a strip 21, fixed to the under side of the bosom-board about midway of its length. Locking-arms 22 are secured to ears 23, pendent from a strip 24, secured to 5 the rear of the bosom-board, and project forward, being centrally provided with slots 25 to receive pins 26, secured to the arms 17. The forward ends of the locking-arms are slotted at 27 to leave upper and lower projecting fingers 28 and 29, the former of which is considerably shorter than the latter, whereby to guide the locking-arms to operative position, as hereinafter described.

The opening 16 in the table is preferably 15 formed with an inclined wall—that is, the edge of said opening inclines inward from the vertical in a downward direction, and the edge of the bosom-board is correspondingly formed, whereby to insure a snug and supporting fit of the parts. The table is braced adjacent the opening by longitudinal strips 30, in which strips is mounted a rod 31, extending transverse of the bosom-board opening 16. One of the arms 17 is projected some 20 distance beyond its pivotal connection to the strip 19, whereby to provide an operating-handle 32.

Assuming the bosom-board in lowered position, its operation in being projected to operative position is as follows: The handle 32 is depressed, moving the board upward on its pivotal connections until the lower arm 29 of the locking-arms contacts with the cross-rod 31, when the board is moved slightly forward 30 to engage said cross-rod and the recesses 27 in the ends of the locking-arms, thus holding the board in elevated position. To return the board to normal or lowered position, it is moved slightly rearward to disengage the 35 notches 27 and the rod 31, when the board may be simply pressed down into its opening flush with the surface of the table, it being understood that the various pivotal connections guide the bosom-board into the opening 16. 40 An ironing-table 33 is supported from the forward end of the table proper, being removably secured thereto. A plate 34 is secured to the forward lower surface of the table and is formed with a pair of slots 35, the outer 45 edge of the plate in advance of the said slots being downwardly bent or offset to form depressed seats 35' for the reception of straps 36, secured to the under side of the table 33. The straps are provided at their inner ends 50 with downwardly-bent lugs 36' to enter the slots 35, and thereby removably connect the table 33 with the plate 34. By preference the edge of the table and the contacting edge of the ironing-board are inclined from the 55 vertical to provide for additionally supporting the ironing-board. Adjusting-arms 37 are pivotally connected at their upper ends to the ironing-board and formed at their lower ends with notches 38, arranged to engage the cross-bars 8 of the forward pair of

legs, whereby to maintain the ironing-board in elevated position. The adjusting-arms are preferably connected to the board near the free or reduced end thereof and diverge from their pivotal connections to spread their lower ends, the arrangement being such that the notched ends of the arms engage the cross-bars 8 practically at the junction of the latter and the legs 6, whereby the legs act as a side brace to the adjusting-bars.

The connection, removal, and adjustment of the ironing-board to secure a desired inclined or horizontal position of the same is obvious from the above description taken in connection with the drawings. A leaf 39 is 80 hinged to each side edge of the table and preferably held in elevated position by the usual bar 40, pivotally connected in the side strips 3 and turned beneath the leaf when desired.

From the above description it will be seen that I have provided a kitchen table for ordinary purposes having the usual hinged leaves and combined with said table a bosom-board so arranged as to form part of the table-surface when lowered into normal position and adapted to be manually moved above the surface of the table and locked in such position for use. The structure is further provided with legs which are readily adjustable 90 to vary the height of the table, whereby to conveniently adapt it for ordinary uses or for ironing purposes.

I do not wish to be understood as limiting myself to the precise construction herein described, as I consider all obvious mechanical changes as within the spirit and scope of my invention.

Having thus described the invention, what is claimed as new is—

1. An ironing-table comprising a table proper, a bosom-board fitting an opening formed in the table and lying flush with the surface of the table when in normal position, arms pivoted to said board and to the table 100 to permit an elevating movement of the board, locking-bars pivoted to the board and to said arms, and coacting locking means on the table to be engaged by said bars when the board is elevated.

2. An ironing-table comprising a table proper, a bosom-board normally fitting an opening formed in the table, arms pivoted to the table and to said board to permit an upward movement of said board, one of said arms being extended to form a handle for operating the board, locking-bars pivoted to the board and to said arms, and means for engaging said bars and thereby locking the board in elevated position.

3. An ironing-table comprising a table proper, a bosom-board fitting an opening formed in the table, arms pivoted to said board and to the table to permit an elevating movement of the board, one of said arms be-

ing extended to form a handle for operating the board, locking-bars pivoted to the board and to said arms, the free ends of the bars being notched, and a locking device extending transversely of the table and adapted to be engaged by the notched ends of the bars when the board is elevated.

4. An ironing-table comprising a table proper, sets of legs pivotally connected to the ends of the table, sets of hanger-bars pivoted to the table at its ends, a rod arranged transversely of the table, the opposite ends of said hanger-bars being connected to said rod, adjusting-bars connecting said rod and the lower ends of the legs, braces connecting the legs of each set, an ironing-board connected to one end of the table, and locking-bars pivoted to said board and adapted to engage the braces of the adjacent set of legs when the latter are extended.

5. An ironing-table, comprising a table proper, means for adjusting the height of the table, a bosom-board fitting an opening formed in the table and lying flush with the surface of the table when in normal position, 25 arms pivoted to said board and to the table to permit an elevating movement of the board to a position above the table, locking-bars pivoted to the board and to said arms, the free ends of the bars being notched, and a 30 rod arranged transverse of the table-opening to be engaged by the notched ends of the bars when the board is elevated.

In testimony whereof I affix my signature in presence of two witnesses.

LEWIS CALVIN BULLOCK.
